RAILWAY TRAFFIC CONTROLLING
APPARATUSGeorge W. Baughman, Pittsburgh, Pa., assignor
to The Union Switch & Signal Company,
Swissvale, Pa., a corporation of Pennsylvania

Application December 23, 1932, Serial No. 648,608

7 Claims. (Cl. 246—34)

My invention relates to railway traffic controlling apparatus, and more specifically to apparatus for providing an indication to a wayside operator that a train has vacated a given track section, or for clearing out a highway crossing cut section upon the exit of a train, as well as for clearing out detector track sections generally.

One object of my invention is to provide apparatus of the above character which will not cause improper operation of cab or wayside signals in a code system of train control and wayside signaling. Another object is to eliminate the necessity for control line wires in accomplishing the above result. Other objects and advantages will become apparent from the description which follows.

I will describe one form of apparatus embodying my invention, and will then point out the novel features thereof in claims.

The accompanying drawing is a diagrammatic view showing one form of apparatus embodying my invention as employed to provide a "track clear" indication at a wayside location such as an interlocking tower.

Where it is desired to restore highway crossing signals to the inoperative condition upon the passage of a train, or to provide a visual or an audible wayside indication that a train has cleared a given section, and in general wherever

control must be exercised over indicating or detecting equipment associated with a given section, it is essential that the control function be performed in such manner that the safety factor of the signaling system will not be impaired there-

by. If control line wires are available, these can be used to transmit the indicating or detecting energy from the leaving end of the section to the desired location, as soon as the section becomes unoccupied. Where such line wires are not avail-

able, it becomes necessary to transmit the clearing or indicating current over the rails of the track and this must be done in such manner as not to cause undesired operation of locomotive-carried cab signaling equipment should a locomotive overrun a signal location and enter the detector section when the next cut section in ad-

vance is occupied. Also, the method used must not decrease the broken down insulated rail joint protection involving staggered track circuit polarities. The system herein disclosed meets the above requirements and is of general utility in providing detection or indication control in coded track circuit signaling systems.

Referring to the drawing, the detector track sec-

tion D—E, over which traffic normally moves from left to right, is supplied with alternating current from a track transformer T¹ having a secondary winding 5 connected across the rails of the track at the exit end of the section through a current limiting impedance 6. Associated with track transformer T¹ is a continuously operating current interrupter or code transmitter CT in which, for purposes of illustration, it will be assumed that contacts 180 and 50 become closed at the rate of 180 and 50 times per minute, respectively.

The auxiliary relay A may be controlled by the track relay TR¹ of the next section in advance, becoming deenergized when relay TR¹ is shunted by a train entering the advance section, or, if desired, relay A may be controlled manually from a wayside location at which an operator may wish to obtain an indication of the occupied or unoccupied condition of section D—E. When relay A is energized, contact 180 of transmitter CT is effective to code the current supplied to winding 4 of transformer T¹ from the source X—O, at the rate of 180 interruptions per minute, over front contact 8 of relay A.

Connected across the rails at the entrance end of section D—E is a two-element code following track relay TR, having a track winding 2 and a constantly energized local winding 3. Relay TR is so designed that it will follow the track current impulses supplied by transformer T¹, closing contacts 9—10 and 9—11 alternately, thereby sup-

plying direct current from a source B—C first to one-half and then to the other half of the primary winding of transformer T², to induce an alternating potential across the secondary winding of this

transformer. The full wave rectifier R¹ is connected across a portion of the circuit involving reactor X¹ and condenser C, which circuit is tuned to the 180 code frequency. Rectifier R¹ supplies

unidirectional current to the relay F, which therefore remains energized as long as relay TR is following track current impulses of 180 code frequency.

When relay F is energized, front contact 12—13 will be closed, and lamp G of signal S will be lighted from the source X—O, to provide a proceed indication. When section D—E is occupied, relay TR will be shunted and will cease to operate, so that the potential across relay F will collapse, and back contact 12—14 will become closed, energizing lamp R of signal S to provide a stop indication for following traffic.

As soon as the train leaves section D—E, relay TR¹ will become shunted, and the release of this relay may be used to deenergize relay A in any

suitable manner, so that back contact 15 of relay A will become closed to complete the circuit for secondary winding 7 of transformer T³ through condenser C² and the periodically closed contact 50 of transmitter CT. Back contact 8 of relay A will also be closed, to supply steady alternating current to primary winding 4 of transformer T¹.

The capacity of condenser C² is so chosen with respect to the reactance of windings 7 and 6 of transformer T³ that the numerical impedance value of winding 6 will not change very greatly irrespective of whether the circuit of winding 7 is closed or open. That is, the change in phase angle and impedance of winding 6 is such that the magnitude of the track current will remain substantially the same whether the circuit for winding 4 of transformer T¹ is being coded over contact 180 of transmitter CT with winding 7 of transformer T³ open-circuited, or whether winding 4 is being supplied with steady energy over back contact 8 of relay A, and the circuit of winding 7 is being periodically closed through condenser C².

Since relay TR is of the two-element type, it is apparent that it can be operated by changes in phase relation of the currents in the two elements, without necessarily changing the magnitude of either of these currents.

The periodic closing of the circuit of winding 7 by contact 50 of transmitter CT, although not appreciably affecting the magnitude of the track current, will, however, periodically change the phase of the track current with relation to the current flowing in local winding 3 of relay TR to a sufficient degree to cause operation of relay TR in step with the operation of contact 50. That is, by proper proportioning of the parts, relay TR can be made to pick up when the circuit of winding 7 is open, and to release when this circuit is closed.

Since the code impulse receiving and translating equipment on a locomotive is so designed as to be insensitive to a phase change of the track circuit current, being in the nature of a single phase device, it will be apparent that the above current of periodically varied phase will cause no cab signal response, thereby eliminating the possibility of a false signal being displayed aboard a locomotive which may have entered section D—E during occupancy of the next section in advance.

The operation of relay TR in following the 50 impulse per minute "phase code" causes relay K to become energized, so that this relay will close its front contact 16 to energize indicator L, which provides an indication that section D—E has been cleared by the train. Since relay F and the energizing circuit therefor are designed for selective response to track current of 180 code frequency, transmission of the above "phase code" over the rail circuit will not affect the indication of the wayside signal S which, so far as the apparatus here illustrated is concerned, will give the "stop" indication as long as relay A is deenergized.

In practice, the code transmitter CT may furnish several codes of different periodic frequencies to selectively control multiple aspect cab and wayside signals in accordance with traffic conditions in advance, the use of but one such signal control frequency being sufficient, however, to illustrate the novel features of my invention. Also, "phase codes" of different frequencies selected in accordance with traffic conditions can be used to provide any one of several distinct wayside indications to apprise the operator of the location of trains in advance sections, or for any other suitable purpose, without affecting cab or wayside signals.

Obviously, the phase shifting circuit used in conjunction with track transformer T¹ can be varied in numerous ways, to accomplish the desired result which involves operation of a "phase code" following track relay to control an indicating or detector circuit under such conditions as will not cause undesired operation of the wayside and cab signals. For example, winding 7 can be eliminated and contact 50 of transmitter CT may be used to periodically connect a condenser, resistor, or other suitable impedance directly across the current limiting winding 6, or if preferred, a phase shifter of suitable design may be connected into the circuit of winding 4 of transformer T¹ in such manner as to produce the desired track circuit current shift each time that contact 50 is operated.

If the locomotive cab signaling equipment is of such character as to permit some change in the magnitude of the track circuit current between the successive impulses of the "phase code" without causing operation of the cab signals, then operation of the relay TR under this condition can be effected by the combination of a change in the magnitude of the current together with a change in phase. The apparatus herein disclosed can also be used to control a railway switch in interlocking territory, in such manner, for example, as to prevent operation of the switch until a train has cleared the section in which the switch is located.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a source of alternating current, a two-element track relay having one element energized from said source and having the other element connected with the rails at one end of said section, means for supplying current from said source to the rails at the other end of said section, means located at said other end of said section and associated with said current supplying means for periodically changing the phase of the current supplied to said rails in such manner that the magnitude of said current remains substantially constant, the change in phase being sufficient to cause said track relay to follow said periodic phase changes, and train detecting apparatus controlled by said track relay.

2. In combination, a section of railway track, a source of alternating current, a two-element track relay having one element energized from said source and having the other element connected with the rails at one end of said section, a circuit for supplying current from said source to the rails at the other end of said section, means located at said other end of said section and associated with said current supplying circuit for periodically changing the phase characteristic of said circuit without substantially altering the magnitude of the current supplied to said rails to cause said track relay to follow said periodic phase changes, and train detecting apparatus controlled by said track relay.

3. In combination, a section of railway track, a source of alternating current, a two-element track relay having one element energized from said source and having the other element connected with the rails at one end of said section,

5 a circuit for supplying current from said source to the rails at the other end of said section which circuit includes an impedance having an appreciable phase angle, means for periodically changing the phase angle of said impedance in such manner that the current supplied to said rails will remain substantially constant in magnitude but will be periodically changed in phase to cause said track relay to follow said periodic 10 phase changes, and train detecting apparatus controlled by said track relay.

10 4. In combination, a section of railway track, a source of alternating current, a two-element track relay having one element energized from said source and having the other element connected with the rails at one end of said section, a circuit for supplying current from said source to the rails at the other end of said section which circuit includes a reactor, means for periodically connecting a condenser of such value across said reactor that the current supplied to said rails will remain substantially constant in magnitude but will be periodically changed in phase to a sufficient degree to cause said track relay to follow 15 said periodic phase changes, and train detecting apparatus controlled by said track relay.

15 5. In a coded alternating current track circuit system of railway signaling wherein traffic governing apparatus is controlled in accordance with the frequency of periodic variations in magnitude of the rail current, the method of providing train detection which involves the application of alternating rail current of substantially constant magnitude but periodically shifted phase to the rails 20 at the exit end of the section when the section next in advance becomes occupied to effect operation of train detecting apparatus connected to the rails at the entrance end of the section and responsive to said periodic phase shifts of the rail current, without affecting the condition of 25 said traffic governing apparatus.

25 6. In combination, a section of railway track, a source of alternating current, a two-element

track relay having one element energized from said source and having the other element connected with the rails at one end of said section, means for at times supplying current periodically interrupted at a given frequency and for at other times supplying current periodically phase-shifted at another frequency from said source to the rails at the other end of said section whereby said track relay will follow said periodic interruptions as well as said periodic 10 phase shifts of said rail current, traffic controlling apparatus governed by said track relay when said relay is following said periodically interrupted current, and train detecting apparatus governed by said track relay when said relay is 15 following said periodically phase-shifted current.

7. In combination, a first section of railway track, a source of alternating current, a two-element track relay having one element energized from said source and having the other element connected with the rails at one end of said first section, said track relay being arranged to follow periodic variations in magnitude as well as periodic variations in phase of the current 20 in said other element, means effective when the next section in advance becomes unoccupied for supplying current periodically varied in magnitude at a given frequency to the rails at the other end of said first section, means effective 25 when said next section becomes occupied for supplying current periodically varied in phase at another frequency to the rails at said other end of the first section, decoding means governed by said track relay selectively responsive to the frequency of operation thereof, traffic governing apparatus controlled by said decoding means when said relay is operating at said given frequency, and train detecting apparatus controlled by said decoding means when said relay is operating at said other frequency. 30 35 40
